UNITED STATES PATENT OFFICE.

MALCOLM MACPHERSON, OF NEW YORK, N. Y.

TOWEL-RACK.

1,072,135.

Specification of Letters Patent.

Patented Sept. 2, 1913.

Application filed December 21, 1912. Serial No. 737,930.

To all whom it may concern:

Be it known that I, MALCOLM MACPHERSON, a subject of the King of Great Britain, and a resident of the borough of Brooklyn, city of New York, county of Kings, and State of New York, have invented a certain new and useful Towel-Rack, of which the following is a specification.

10 My invention relates to a device for holding and retaining a number of towels; and the object thereof is to provide a device for holding a number of towels in such a way that they may be individually separated 15 from a stack or supply of unused towels, be individually used while separated from the supply of clean towels as well as the soiled ones, and then be placed with the soiled or used towels; the towels at all times being 20 retained or held so that they can not be accidentally or intentionally removed from the device. The purpose thereof is to prevent the loss of towels in public or private places, especially in department stores, rail- 25 road trains and such like, where large numbers of towels are continually at the disposal of users generally, and where the towels can not be always cared and accounted for by attendants.

30 With the employment of my present device a number of individual towels may be supplied to the device and be locked in connection therewith until such time as they are to be removed and replenished by one 35 having the authority to do so. Users may individually disengage or remove a towel from the supply, such as a stack, use the towel, and then place the used towel out of the way of subsequent users, and during 40 as well as before and after use, the towels are retained by the device in a manner which will prevent their being carried away or lost. While a towel is being used it is moved from the supply or stack so that the 45 towels in the latter are not soiled, and it is also at such time separated from the previously soiled towels so that the user need not come into contact therewith.

The device is very simple, inexpensive and 50 efficient for carrying out the above objects.

The device is very handy and the manner of its use is obvious from its construction.

In the drawing forming a part of this application, Figure 1 is a plan view, showing my invention attached to a wall or other 55 convenient support, in which view the towels

are shown as double towels, that is, they are secured at their middle portion and each half is adapted for individual use, Fig. 2 is a sectional view, taken on the line 2—2 60 of Fig. 1, Fig. 3 is an end elevation thereof, with the towels and weight removed to show the construction of the device, Fig. 4 is a sectional view, showing the members which engage the towels and prevent their 65 removal from the device, and Fig. 5 is an end view of a modified form of device, wherein a plurality of posts are employed.

The means for holding the supply of unused towels may be variously formed, but 70 I prefer to employ a rack, here shown as consisting of a rectangularly shaped bar or rod 1, and cross bars or supports 2, 3, 4, 5. In the form of my invention shown in Figs. 1 to 4, there is a cross member 6 between 75 the portions 7, 8 of the rectangular bar or frame, which supports an upwardly extending holding member or post 9 which receives and holds the towels. The cross member 6 has a socket member 10 in which 80 the post is secured and by which it is supported.

The above parts may be suitably supported in any desirable location, and for convenience I have shown, in Figs. 1 and 2, a 85 supporting bracket, consisting of an upright end 11, which fits into the lower end of the socket member 10, a laterally extending portion 12 which extends out beyond the rack; and a downward portion 13 which may be 90 suitably secured to the wall or other support 14 by means of a clamp 15.

There is arranged to slide over the post 9 a sleeve 16, to which is secured a cross arm 17, here shown as extending horizontally in opposite directions from the sleeve, and provided with upturned ends 18. The towels 19 are each provided with an opening 20 preferably near the center thereof, which opening may be suitably finished, as 100 by stitching the edge thereof. The towels are placed over the sleeve 16 while the same is separated from the rack, by passing the sleeve through the apertures 20 of any number of towels, say several dozen, or whatever 105 the supply is to be; and the towels are allowed to slide on the sleeve until they rest on the cross arm 17. The sleeve 16, together with the towels, is then slipped down over the post 9 and is secured thereto by suitable 110 means, such as a padlock 21 the bail of which passes through alining apertures 22

in the post and sleeve. When so secured, the towels can no longer be removed except by a person having a key to the lock, because the sleeve is secured to the post and 5 the towels can not be moved downwardly off the sleeve nor can they be moved upwardly and off the same, because their apertures are too small to allow them to be moved over the lock.

10 When the towels are arranged upon the post, as above described, they will be so placed that they extend forwardly and rearwardly from the arm 17 and rest upon suitable supports which hold them in suitable 15 condition. To one side of the place where the towels are secured, there are supports 2, 3, arranged to project inwardly from the portions 7, 8, of the rack frame. They are arranged to project toward each other, as shown in Fig. 1, but they do not 20 meet, a space 23 being left between them, for a purpose which will be apparent hereinafter. The members or support 2, 3, are here shown as U shaped rods disposed horizontally, and they serve the purpose of supporting one half or one end of the stack of towels.

In the form of my invention shown in Figs. 1 to 4, a second pair of supports 4, 5 30 is provided for the other end or half of the stack of towels; and they are located in similar relative positions to the supports 2, 3, but toward the opposite end of the rack.

35 In addition to the above, separators are provided for keeping the towel which is in use separated from those which may have been previously used and which have become soiled. The device for this purpose is 40 here shown as consisting of downwardly extending members 24, 25, which are preferably arranged below the towel stack and on a line between the supports 2, 3, and the post 9. These separators are here shown 45 as consisting of plates supported by rectangular hoops 26 to which they are fastened. The bars 26 forming the hoops extend upwardly and connect with the rack frame. The plates 24, 25 are preferably 50 arranged in the same plane, but are separated to form an intermediate space 27. Similar separators 28, 29 are arranged on the side of the towel bar 17, opposite to the separators 24, 25.

55 When the stack of towels is placed in position over the post, preferably a weight 30 is placed on the stack to keep the towels in flat condition and to insure their following down into position as successive towels are 60 used.

When the towels have been placed in position as shown in Fig. 2, they will rest on the cross arm 17 and upon the supports 2, 3, 4, 5. The ends of the lowermost towels 65 preferably droop, as at 31, beyond the sup-

ports 2, 3, 4, 5, respectively, so that the ends of the lowermost towel will be accessible to the user. When it is desired to use a towel, or rather one half thereof, the end of the lowermost towel is grasped, preferably near the middle thereof and is pulled downwardly. As the end of the lowermost towel is thus pulled it will pass between the supports 2, 3, that is, through the space 23 between the supports, until it hangs in the position shown in Fig. 2, and indicated by the reference character 32. In this position the towel will droop over the frames or hoops 26 and will be accessible for use, and the towel may be made use of while thus separated from both the stack of unused towels and any which have been previously used. When the towel has been used, the end thereof is pulled until it passes between the separators 24, 25 or through the space 27, when it will be allowed to hang from the arm 17 as shown at 33, (Fig. 2), on the opposite side of the separator to that where it was when used. In similar manner the end of the towel now lowermost in the stack may be brought down, used, and then moved behind the separator, similar to the first one; and so on, until all the towels in the rack have been used. The opposite halves of the towels, shown on the right of Fig. 2, may be similarly brought down between the support 4, 5, used, and then placed behind the separators 28, 29. Thus the towels may be used from each end independently, so that two persons may simultaneously make use of the device. When all the towels have been brought down, and used, the stack may be removed, upon removing the lock, by lifting off the sleeve 16 arm 17 and the towels therewith, and a fresh stack put in the place of the first one.

If desired the device may be formed as a single rack, that is, so that the towels will be used only from one end. In that case one half the rack frame will be omitted leaving only the members 7, 8, cross piece 8^a and the cross piece 6, which latter will now come at the end of the rack as shown in Fig. 5. In this form of my invention it is preferable to have two posts 9, arranged in sleeves 16 and the cross arm 17 is provided with sockets 10, one for each post 9. The towels for this form of rack will then require two holes, which will be arranged near the end thereof. The device will then be substantially one half of that shown in Figs. 1 and 2, and will be used in a similar manner.

From the above it will be apparent that I have provided a very simple, convenient and inexpensive rack wherein towels may be individually separated from the supply or stack, used while separated therefrom and from any previously used towels, and be moved away so as not to interfere with the

subsequent use of others; and wherein the towels will not be accidentally or intentionally removed or stolen.

Having described my invention, what I claim is:—

1. A device of the character described, comprising a supporting rack for holding a stack of towels in substantially horizontal position, a depending separator for retaining the towels in separated relation after their removal from the stack, the towels being movable through the said support and said separator, and means engaging the stack of towels and arranged to retain the towels while in the stack and after their separation therefrom.
2. A device of the character described, comprising a horizontally disposed supporting rack having inwardly extending supporting members for supporting a stack of towels, separated from each other near the middle of the rack to permit the towels to be individually drawn therethrough to separate them from the stack, depending separating members, extending inwardly toward each other but separated to permit the towels to be drawn therethrough after their separation from the stack, and means engaging through the towels and arranged to retain them while in the stack and after separation.
3. A device of the character described, comprising a rack for supporting a stack of

towels, an upwardly extending post engaging through the towels, said rack having 35 spaced supporting members adapted to allow the towels to be individually drawn therethrough to separate them from the stack, depending, spaced separating members, arranged below the rack and forward of the 40 said post, and between which the towels are adapted to be drawn, for the purpose set forth.

4. A device of the character described, including a horizontal rack comprising a rectangular frame, a post extending upwardly therefrom, for receiving the towels thereover, supporting members arranged on opposite sides of said post, and extending inwardly from opposite sides of said frame 50 and spaced apart in line with the post, a sleeve slideable on said post and having a lateral arm to receive the towels, means for securing a stack of towels on said post, and depending separating members arranged on 55 opposite sides of the post, and comprising members extending inwardly toward, but spaced from each other in line with said post.

Sworn in the city, county and State of 60
New York, this 20th day of December, 1912.
